UNITED STATES PATENT OFFICE.

GEORGE B. STREIT, OF DETROIT, MICHIGAN.

MAILING-PACKAGE.

1,067,948.

Specification of Letters Patent.

Patented July 22, 1913.

Application filed July 3, 1911. Serial No. 636,626.

To all whom it may concern:

Be it known that I, GEORGE B. STREIT, a citizen of the United States, residing at Detroit, county of Wayne, State of Michigan, have invented a certain new and useful Improvement in Mailing-Packages, and declare the following to be a full, clear, and exact description of the same, such as will enable others skilled in the art to which it 10 pertains to make and use the same, reference being had to the accompanying drawings, which form a part of this specification.

This invention relates to mailing packages, and has for its object a package adapted to be cut from a single blank and which can be securely fastened together without clasps or other metallic fastening means.

In the drawings:—Figure 1, is a perspective of the blank. Fig. 2, is a perspective of the blank showing the ends folded into upright position. Fig. 3, is a perspective of the box. Fig. 4, is a perspective of the box with the cover fastened down. Fig. 5, 20 is a section on the dotted line 4—4 of Fig. 4. Fig. 6, is a perspective of the blank of a modified form of this mailing-package. Fig. 7, shows the blank of Fig. 6 with the ends raised in upright position. Fig. 8, 30 shows the finished box of the modified form. Fig. 9, is a perspective of the box of the modified form with the cover fastened down.

This invention consists of a blank scored 35 to form a number of rectangular strips. Four such strips are required in the form shown in Fig. 1, being indicated by the letters B, C, N, and J. At one end of these strips a flap A adjoins and is scored at its junction with the rectangular strip B. This flap has at one side a lobe a, and at 40 the other side a lobe a¹, and between these two lobes at the end of the blank a lobe b. At the sides of the blank and at each end 45 of the strip N, which is the third strip removed from the flap A, end portions of the box adjoin in the blank. The end portion at one side of the blank comprises the rectangular end-piece R having on opposite 50 sides two stay pieces j and K and on the remaining side the locking-flap.

The end portion at the opposite side of the blank comprises the end-piece S, which is at one side integral with the rectangular 55 strip N and has adjoining it on two opposite sides the stay-pieces X and m, and,

adjoining it on the remaining side, the locking-flap I. The rectangular strip J in the main portion of the blank, adjoining the strip N, has slots d and c cut at each 60 end. These slots are intended for the reception of the lobes a and a¹, and their position is calculated so that they will register with the lobes when the flap is folded down on the strip J. Between these slots a slit 65 e is provided, in which the lobe b slips.

At the end of the blank opposite from the flap A, and adjoining the rectangular strip J is a locking strip P, which in its general contour is rectangular, but which has at 70 each outside corner notches cut forming locking-portions p and p¹. These locking-portions are preferably formed by cutting a slit running from the end of the blank into the strip P parallel with the sides 75 but short of the scored line which divides the strip P from the strip J. About half of the substance included between the cut and the edge of the blank is then clipped off in a curved cut. The locking-portion 80 p¹ at the other side of the strip is formed in a like manner, as are also the locking-pieces s and s¹ in the strips H and I.

The above directed cuts having been made, and the above described strips having been marked off from their adjoining strips by scoring the blank at their junctions, the blank is complete and ready to be folded into box form. The end pieces are then raised as shown in Fig. 2 and the stays 90 j and K folded in and into right-angular relation with the end-piece R and the stays X and m are likewise folded in and into right-angular relation with the end-piece S. The rectangular strip J is then folded up 95 against the stays K and m and the strip P interlocked with the locking-flaps H and I by slipping the locking-piece s of the flap H over the substance of the strip P next adjoining the cut, and the tongue of the 100 locking-portion p over the portion h of the flap H. This forms a firm interlock and the locking-piece s¹ and locking-portion p¹ on the other side being likewise interlocked, the strip P is firmly locked to the ends R 105 and S and parallel to the strip N which forms the bottom of the box. These two engagements of the locking flaps I and H with the locking strip P form corner interlocks. Each corner interlock has, as constituent members, a locking flap and a portion of the locking strip P. The other end 110

of the blank is now folded into position, the strip C folded up against the pieces *j* and *X* which act as stay members, and the strip B closing over the interlocked strip 5 *P* and flaps *H* and *I*, while the flap A folds over ready to be fastened to the strip *J*. The fastening may be readily accomplished by slipping the lobes *a* and *a'* into the openings *d* and *e* respectively, and pushing the 10 lobe *b* into the slot *e*. In the completed box the strips C and J form the sides, the strip N the bottom, the end-pieces R and S the ends, the pieces *j*, *K*, *X* and *m* form the stays, the strip *P* interlocking with 15 the pieces *H* and *I*, and forming the top of the box, and the strip B folds over and covers the top, while the flap A interlocks with the strip *J* and closes the box.

In the modified form shown in Figs. 6-9 20 the strip B which serves to cover the top of the box is omitted, as is also the lobe *b*. The strip *P* is interlocked with the end pieces *H* and *I* by providing slits *f* and *f'* in which the locking pieces *s* and *s'* may be 25 slipped in place of interlocking over the edge of the strip *P*, as in Fig. 3, and the lobes *a* and *a'* of the flap A are slipped into slits *u* and *u'* of the locking flaps *H* and *I*.

30 My corner interlock consists primarily of at least one tongue on one of the constituent members which is free at one side, but closely adjoins the substance of the member upon which it is carried on the other side, that is, the tongue is integral with the locking-flap or locking strip (depending upon which member carries it) at one of its ends, it is also free at one side because it is located at the corner of the blank, but at the 35 opposite side it is closely adjacent the member which carries it for it is only separated therefrom by a slit. For the purpose of clearness of reference the portion of the member carrying the tongue that directly 40 adjoins the tongue on the side and constitutes the remainder of the locking-piece will be designated the lap-piece, for its function is to lap over a portion of the other constituent member of the corner interlock. 45 The tongue can be slipped through a slit such as shown at *f* or *f'* in Fig. 8 or it may be slipped under the substance of the blank adjacent a similar tongue in the other constituent interlock (Figs. 1, 2, and 3). This 50 latter form is my preferred form of construction, but it will readily be seen that almost equivalent results are accomplished by either form of the locking-portion. The 55 essential thing in the interlock is the presence, in one constituent member of the interlock, of the tongue closely adjacent at one side to a lap-piece and the presence of a locking portion, such as either a slit or a similarly formed tongue, in the other constituent member of the interlock. Either 60

form of construction allows the tongue and the lap-piece to divide, one portion lying on one side of the locking-portion of the other constituent member of the interlock, while the other portion lies on the opposite side of 70 the locking-portion. I, therefore, wish it understood that when the locking-portion is referred to in the claims it covers both forms.

What I claim is:—

1. A mailing package formed from an integral blank, comprising a bottom having portions projecting from the ends thereof adapted to form the end walls of the package, said portions being provided with locking flaps projecting therefrom each having a slit extending inwardly from one side thereof parallel to the outer edge thereof, said bottom being provided with a portion projecting from one side thereof adapted to 75 form one side wall of the package, and having a locking strip extending therefrom provided with locking slits extending inwardly from the outer edge and parallel to the ends thereof adapted to interlock with the locking slits of the flaps of the end portions when the sides and end portions of the blank are folded, said bottom being also provided with a portion projecting from the other side thereof of a length when folded 80 to form the other side wall of the box and to overlie the interlocked locking members of the side and end portions and provided at its free end with laterally projecting locking flaps, the blank being provided with 85 slits to receive said laterally projecting locking flaps.

2. A mailing package, having in combination, a plurality of joined strips, the end strips of which are, one a locking strip and 90 the other a cover flap, all the said strips being marked off from one another by scorings so that adjoining strips are foldable perpendicular to each other to form the bottom, two sides, said locking strip and the cover 95 of the package; end pieces, one adjoining each end of one of the interior strips and marked off from such strip by a scoring so as to be foldable perpendicular thereto; a locking flap adjoining each end-piece at its 100 end and marked off therefrom by a scoring so as to fold perpendicular to the end piece; the said locking flaps having each a cut near one corner and the said locking strip having a cut near each outside corner; the said two 105 locking flaps and the said locking strip being capable of interlocking at their cut corners to form two corner interlocks; the said cuts forming in one of the constituent members of each of said corner interlocks a locking-piece which comprises a tongue and a 110 lap piece, and forming in the other constituent member a locking-portion to receive the locking-piece and cut so that the tongue of the locking-piece may be caused to lie on 115

one side of the locking portion and the lap-piece may be caused to lie on the other side of the locking portion; and means in connection with one of the said first mentioned strips that forms one of the sides of the package for securing the cover flap thereto, substantially as described.

In testimony whereof, I sign this specification in the presence of two witnesses.

GEORGE B. STREIT.
